UNITED STATES PATENT OFFICE.

FRANCIS M. BARTON, OF CHICAGO, ILLINOIS.

CONCRETE WALL CONSTRUCTION.

Application filed October 23, 1924. Serial No. 745,278.

The invention relates to concrete wall constructions and its primary object is to provide an improved method of, and means for, forming grooves having constricted entrance in the concrete wall, and which are adapted for the wall ties.

The invention consists in the several novel features hereinafter set forth and more particularly defined by claims at the conclusion 10 hereof.

In the drawings: Fig. 1 is a horizontal section showing a form in position in a concrete wall. Fig. 2 is a similar view, showing one of the form sections removed therefrom. Fig. 3 is a modified form of the invention, in which the form is adapted to produce a wide groove and is formed of three sections. Fig. 4 is an elevation, showing the manner of anchoring brick facing 20 to a concrete wall by means of ties held in the grooves. Fig. 5 is an elevation, showing the use of brick ties and wide grooves for tying a brick facing to the concrete wall. Fig. 6 is a section on line 5—5 of Fig. 4. Fig. 7 is a section on line 7—7 of Fig. 5. Fig. 8 is a perspective, and Fig. 9 a horizontal section of the tie shown in Figs. 4 and 6. Fig. 10 is a perspective showing the groove-forms in the concrete wall. Fig. 11 30 is a perspective of the wall after the forms have been removed, and a tie held in the groove.

In the construction of concrete walls, it has heretofore been proposed to use channelled metallic members embedded in the concrete wall to provide grooves for securing ties or anchors for a brick or other facing to the concrete wall. This has been found to increase the cost of erection, because of the high cost of the steel liners. The primary object of the invention is to provide a method of forming dove-tailed grooves or grooves with constricted entrances in the concrete wall in such a manner that the liners may be dispensed with. This object is attained by providing a form composed of separate strips which are adapted to produce grooves of the desired shape in the concrete wall and are removable therefrom when the concrete has set, thus dispensing with the necessity of leaving any metal in the grooves in the concrete wall.

In the form of the invention shown and illustrated in Figs. 1 and 2, the form is composed of longitudinally extending sections 55 10 and 11. Each of these sections comprises

an inwardly flared side 12, a back flange 13 and a front flange 14. The back flanges 13 are extended to meet centrally of the grooves. The sides are flared inwardly, so that the entrance to the groove will be constricted to adapt it for holding ties therein.

The back flanges 13 are extended to meet on a central line of the groove. The front flanges 14 are usually attached by nails 15 or other suitable means to the wooden strips 16 which are adapted to form the outer face of the concrete wall 17. When the concrete has been poured to form the wall, an integral mass thereof will extend around the 70 back and sides of the sectional form. The latter is formed of strips of convenient length for handling. In practice, strips four feet in length have been found to operate satisfactorily. These strips are laid end to end to form continuously extending grooves of any desired length or height. When the concrete has set around the groove form, the form boards 16 will be removed. Then the section 11 of the form can be removed from the wall, as indicated by dotted lines in Fig. 2. To permit this to be done, the side is formed so that when it is swung about a point at the meeting edges between the sections, the side 12 will be free to swing inwardly from, and clear the contiguous face of, the groove side in the concrete 17. After the section 11 has been removed, the section 10 may be similarly removed. In removing the form, the sections are swung or moved transversely of the groove. The forms could not be practically separated by longitudinal movement in the groove. When the form has been removed, a groove with a back 19, rearwardly flaring sides 20, conforming to the outer faces of the form-sides 12, and a groove 21 will be formed in the concrete wall, and this groove may extend the full length or height of the wall, if desired.

The flanges 14 will form a recess at the sides of the groove. In the form illustrated, the rear portions of the form-sides are curved or arched on a radius that is greater than the radii on which the sections fulcrum in their removal from the wall and this has been found to render the grooved form readily removable after the concrete has set.

In Figs. 4 and 6, there is shown a facing wall 22 of brick, which is laid in front of the concrete wall 17 and is anchored thereto 110 by ties consisting of wire loops 23 and rearwardly flared anchor-members 24 which ex-

tend transversely across the groove 25 in the concrete. The sides of said groove are rearwardly flared, as previously described, so that the ends of the anchors 24 will interlock therewith and be held thereby.

In Fig. 3, there is illustrated a modification, which is more particularly adapted for forming grooves of considerable width. In this form of the invention, the groove 10 form consists of sections 10 and 11, similar to those previously described, and an intermediate back plate 13^a. The latter has its margins bent backwardly, as at 13^c, to back lap the inner margins of back members 13 15 and is provided with lugs 13^b to form an interlock between the form sections, by which the intermediate section 13^a will be supported from the sections 10 and 11, the latter being supported from the form- 20 boards 16, as hereinbefore described. After the concrete has been poured around the form and has set, the form will be removed from the wall by first swinging the section 11 transversely, as shown by dotted lines 25 in Fig. 3, then similarly removing the section 10; and then removing the intermediate section 13^a. The intermediate section can be removed forwardly when both of the sections 10 and 11 have been removed. When 30 this form has been removed from the wall 17^a, the latter will be provided with a groove 25^a of any desired length, with a constricted entrance, so that it will be adapted to hold wall anchors.

35 In Fig. 5 and 7, there is illustrated a brick facing 22^a and obliquely laid anchor bricks 23^a which are embedded in mortar and extend obliquely into the groove 25^a to interlock with one of its sides.

40 The invention exemplifies a method for forming, in concrete walls, dove-tailed grooves or grooves having constricted entrances to interlock with wall anchors, in which a metallic lining is dispensed with, 45 the metallic forms being adapted to be removed transversely from the grooves. In this manner, the cost of forming these grooves is greatly reduced, because the forms are adapted for repeated use. The form used 50 makes it possible to remove it, even though the ends of the grooves should be closed, as occurs in some instances.

The invention is not to be understood as restricted to the details set forth, since these may be modified within the scope of the 55 appended claims, without departing from the spirit and scope of the invention.

Having thus described the invention, what I claim as new and desire to secure by Letters Patent, is:

1. In concrete wall construction, the combination of a form for a concrete wall, and a form supported by the wall-form and adapted to form a groove for anchors in one face of the wall, said last mentioned form consisting of separately formed metallic sections having flared sides for producing a constricted entrance in the groove, said sections being removable individually and transversely from the groove through the 70 constricted entrance, after the concrete has set.

2. In concrete wall construction, the combination of a form for a concrete wall, a form supported by the wall-form and adapted to form a groove for anchors in one face of the wall, said last mentioned form consisting of separately formed metallic sections, each of said sections comprising an integral side, back portion, and front flange, 80 the sides of said sections being flared to produce a constricted entrance in the groove, and means connected to the front flanges of the sections for temporarily securing the latter to the wall form, said sections being removable individually and transversely 85 from the groove through the entrance, after the concrete has set and the portion of the wall-form to which the sections are attached is removed.

3. In concrete wall construction, the combination of a form for a concrete wall, and a metallic groove-form supported by the wall-form and consisting of a pair of sections having flared sides for forming the sides of the groove and a separately formed intermediate back section between the side sections and for spacing the latter apart, all of said sections being individually removable from the groove, after the concrete 100 has set.

Signed at Chicago, Illinois, this 11th day of October, 1924.

FRANCIS M. BARTON.
